UNITED STATES PATENT OFFICE.

SAMUEL W. REYNOLDS, OF WEST TOLEDO, OHIO.

SLIP-CLIP.

No. 878,670.

Specification of Letters Patent.

Patented Feb. 11, 1908.

Application filed October 11, 1906. Serial No. 338,407.

To all whom it may concern:

Be it known that I, SAMUEL W. REYNOLDS, a citizen of the United States, residing at West Toledo, in the county of Lucas and 5 State of Ohio, have invented a new and useful Improvement in Slip-Clips, of which the following is a specification.

My invention relates to an improved slip clip and more particularly is adapted for use 10 in connection with check loops on harness or straps.

Among the objects of this invention are simplicity of construction and effectiveness in use.

15 In a general way, my invention comprises an elastic band for tightening the laps of a loop around a hook and for holding said laps so that the loop will not become detached from said hook.

20 In the accompanying drawings forming part of this specification, Figure 1 is a perspective view of a check loop or harness provided with my improved slip clip; Fig. 2 is a cross sectional view of the check loop looking at the end of the slip clip and Fig. 3 is a view showing the parts of the slip clip separated.

For the purpose of illustrating my invention I have shown an ordinary check loop A 30 which is provided with the usual metal eyelet 2 having a shank 3 to which the ends 4 and 5 of the strap loop are secured by means of a rivet 6.

My improved slip clip B is adapted for use 35 in connection with the loop or strap for the purpose of holding the laps of the loop tightly together to prevent said loop being detached from a check hook or other support around which it is placed. This slip clip comprises 40 a pair of slip plates 7 and 8 which rest against the sides 9 and 10 of the laps of the loop. Each of these slip plates has its ends 13 and 14 bent over the edges of a lap of the loop and its edges formed with flanges 15. An elastic

45 band C is placed between the flanges upon the outer surface of the slip plates and passes around the laps, thus pressing the plates tightly against the sides of the loop. The slip plates perform the function of reducing 50 the friction between the clip and loop and the elastic band holds the laps of the loop tightly together to prevent the loop being detached from the hook or other support.

In accordance with the patent statutes I have described the principle of operation of 55 my invention together with the apparatus which I now consider to represent the best embodiment thereof, but I desire to have it understood that the construction shown is only illustrative and that the invention can 60 be carried out by other means and applied to uses other than those above stated within the scope of the following claims.

Having described my invention, what I claim as new and desire to protect by Letters 65 Patent is—

1. A device of the class set forth, comprising in combination laps of a loop or strap, a slip member, and a resilient member co-acting with said slip member to hold said 70 laps.

2. A slip clip having a slip plate, laps of a strap, and an elastic band co-acting with said plate to hold said laps.

3. A device of the class set forth, comprising a pair of laps of a loop or strap, a pair 75 of slip plates on the sides of said laps, and an elastic band around said plates, for the purposes specified.

4. A device of the class set forth, comprising a slip member, laps of a loop or strap, and an elastic band around said member and said laps.

5. A device of the class set forth, comprising in combination laps of a loop or strap, 85 an elastic band around said laps, and a slip member between said band and laps to reduce the sliding friction of said band on said laps.

6. A device of the class set forth, comprising a pair of opposed slip plates, laps of a loop or strap between said plates, and an elastic band around said plates.

7. A device of the class set forth, comprising slip plates having flanges and a dis- 95 tended band around said plates and between said flanges.

In testimony whereof I have signed my name to this specification in the presence of two subscribing witnesses.

SAMUEL W. REYNOLDS.
